UNITED STATES PATENT OFFICE

ALEXANDER S. KATZ, OF BROOKLYN, NEW YORK

DESIGN FOR A LATCH OR SIMILAR ARTICLE

Application filed December 24, 1931. Serial No. 42,193. Term of patent 3½ years.

To all whom it may concern:

Be it known that ALEXANDER S. KATZ, a citizen of the United States, and resident of Brooklyn, New York, in the county of Kings and State of New York, has invented a new, original, and ornamental Design for Latch or Similar Article, of which the following is a specification, reference being had to the accompanying drawings, forming part thereof, in which,

Fig. 1 is a front view of a latch embodying my new design; and

Fig. 2 is a side elevational view thereof.

I claim:

The ornamental design for a latch or similar article, substantially as shown.

Dated, December 22, 1931.

ALEXANDER S. KATZ.
